Primary Examiner — Karen S Acker*Assistant Examiner* — Clare Ann Gannon(74) *Attorney, Agent, or Firm* — Amster, Rothstein & Ebenstein LLP**CLAIM**

The ornamental design for a paper product with a surface pattern, as shown and described.

DESCRIPTION

The sole FIGURE is a plan view of one side of the paper product with a surface pattern showing our new design.

The broken lines define the bounds of the claimed design and form no part thereof. The claimed design repeats uniformly throughout the surface of the paper product with a surface pattern. The design is planar.
